Assignor to

The Lowell Manufacturing Company.

Letters Patent No. 1643, dated Aug. 12, 1862.

The schedule referred to in these Letters Patent and making part of the same,

To all whom it may concern:

Be it known that I, Clemir J. Ney, of Lowell, in the County of Middlesex, and State of Massachusetts, have originated and designed a new Pattern for Carpets or other fabrics, of which the following is a full, clear and exact description, reference being had to the accompanying drawings, making part of this specification,

A, is a veined figure resting on the ground, 1. This ground has an irregular border and is enclosed by a wreath composed of groups of flowers connected by small scrolls.

2, and 3, at the sides when matched form a figure similar to A and resting on the ground 4, which is enclosed by a chain of scrolls and small flowers.

5 and 6, are small irregular figures surrounded by small vines. Fig. 7, is an oblong group of small blocks enclosed by scrolls. 8 and 9, are halves of figures similar to 7. 10, is a ground work of foliage.

The remaining figures in the drawing are either duplicates or sections, of figures similar to those before mentioned.

The colors employed for the different portions of the design may be varied to suit the taste and wish of the manufacturer.

Claim.

What I claim as my invention and desire to secure by Letters Patent, is the design or pattern, for carpets or other fabrics herein set forth.
